UNITED STATES PATENT OFFICE.

JOHN C. DILWORTH, OF PITTSBURGH, PENNSYLVANIA, AND CHARLES S. WEEKS, OF BROOKLYN, NEW YORK, ASSIGNEES TO DILWORTH, PORTER & CO. LTD., OF PITTSBURGH, PENNSYLVANIA, A LIMITED PARTNERSHIP.

AUTOMATIC SPIKE-MACHINE.

1,150,665.

Specification of Letters Patent. Patented Aug. 17, 1915.

Application filed June 13, 1914. Serial No. 844,986.

To all whom it may concern:

Be it known that we, JOHN C. DILWORTH and CHARLES S. WEEKS, citizens of the United States, residing at Pittsburgh, in the county of Allegheny and State of Pennsylvania, and in Brooklyn, in the county of Kings and State of New York, respectively, have invented a new and useful Improvement in Automatic Spike-Machines, of which the following is a full, clear, and exact description, reference being had to the accompanying drawings, forming part of this specification, in which—

Figure 1 is a plan view of one form of our improved machine; Fig. 2 is a longitudinal section of the machine; Fig. 3 is a transverse section on the line III—III of Fig. 2; Fig. 4 is a detail side elevation of the adjusting mechanism for the bearings for the header; Fig. 5 is a side elevation of the machine showing the device for the feeding mechanism; Fig. 6 is a front view; Fig. 7 is a side elevation of the housing for the feeding mechanism from the other side of that shown in Fig. 5; Fig. 8 is a detail side elevation of a portion of the machine showing the die-operating mechanism; Fig. 9 is a side elevation of the cam member for operating the die mechanism; Fig. 10 is a plan view thereof; Fig. 11 is a detail side elevation of the split collars for endwise adjustment of the feeding roll spindles; Fig. 12 is a detail side elevation partially in section of the nippers and their carriage; Fig. 13 is a plan view of the nippers and their operating connections; Fig. 14 is a diagram of the nippers showing them in full lines in their rearmost positions after the blank has been dropped and in dotted lines in their forward position before closing on the next blank; Fig. 15 is a similar view showing the nippers in full lines closed in their forward position and in dotted lines in their rearmost position just prior to dropping the blank into the die; Fig. 16 is a detail side elevation of the ratchet mechanism for actuating the stock-feeding and blank-cutting rolls, the gears being omitted for clearness; Fig. 17 is a sectional view on the line XVII—XVII of Fig. 16; Fig. 18 is a partial plan view of the blank-holding die and a portion of the operating mechanism; Fig. 19 is a sectional view on the line XIX—XIX of Fig. 18; Fig. 20 is a

perspective view of the movable die block; Fig. 21 is a side elevation thereof; Fig. 22 is a plan view of the wedge for actuating the movable die member; Fig. 23 is a side elevation thereof; Fig. 24 is a perspective view of the hardened or anvil portion of the stationary die member. Fig. 25 is a perspective view of the ejector for removing the finished spike from the die; Fig. 26 is a detail side elevation of the nipper-operating connections; Fig. 27 is a detail sectional view on the line XXVII—XVII of Fig. 26; Fig. 28 is a similar view on the line XXVIII—XXVIII of Fig. 27; Fig. 29 is a front view of the stock-feeding and cutting rolls; Fig. 30 is a sectional view on the line XXX—XXX of Fig. 29; Fig. 31 is a detail sectional view on the line XXXI—XXXI of Fig. 5; Fig. 31^a is a detail view hereinafter referred to; Fig. 32 is a transverse sectional view through portions of the die and the gripper, showing a blank in position; Fig. 33 is a longitudinal view through Fig. 32; and Fig. 34 is a diagram illustrating the relative movements of the various parts of the machine.

80

Heretofore, two types of spike machines have been used, one known as the automatic machine and the other as the hand-fed machine. In the automatic machine, the heated bar is fed forward and cut off and pointed by means of feed rings and recessed rollers having knives intermittently turned by a ratchet movement. The cut and pointed spike blank is then transferred by nippers to a solid longitudinal die having two sides and a bottom, into the cavity of which it is dropped. A gripper is then forced down on this blank, which projects slightly above the die and the header then forms the head at one end of the blank. The finished spike is then thrown out in the direction of the header, which has been drawn back by a pin or discharge device, which is forced up through a hole in the bottom of the die. To prevent the spike from sticking when thrown out, the die in this case is formed with side walls which taper inwardly and downwardly toward each other to cause draft. This is objectionable, as it does not form a rectangular spike. Moreover, as the spike blank projects above the top of the die, a portion of the spike head is not die-shaped and consequently is not as well adapted for claw-

85

90

95

100

105

bar engagement in withdrawing from a railroad tie.

In the hand-fed machine, there is no pointing of the spike, this being an after operation. In such machine, the bar is pushed forward by the operator, is cut off without pointing, and is clamped horizontally between one die member having a flat clamping face and another of L-section, the horizontal ledge of the latter serving as a bottom for the complete die and the vertical portion serving as a clamping side. The blank is then clamped vertically between the bottom part of the die and a gripping member, which descends upon the blank from above, and, while thus supported as to its four sides, the head is formed on a portion of the length of the blank which protrudes from the die. In such case, there is, of course, no automatic feeding and no transfer mechanism for engaging a cut blank and transferring it into the die.

Our invention is designed to give the advantages of both the automatic machine and the hand-fed machine, to prevent any sticking of the spike in the automatic machine, to improve the discharging operation and give a better article than heretofore formed in the automatic machines, both by making the opposite sides of the spike body of the same width, doing away with the draft, and by forming a better head by reason of entirely closing the blank.

One of the main features of our invention consists in combining a side-opening die with an automatic feed and pointing device and a transfer mechanism which transfers the pointed blank from the feed and pointing mechanism to the side-opening die. With this combination is also preferably employed a gripper which clamps the cut and pointed blank in the cavity of the side-opening die.

Another feature of our invention lies in providing a removable housing or frame which contains the adjustable feeding and pointing mechanism. Heretofore, in automatic spike machines, the setting and adjusting of the feeding rings, pointing knives, etc., must be carried out in the mill with the parts in the machine. This involves a long delay in resetting and adjusting, whereas in our improved system this setting, adjusting and changing operation may take place independently of the machine and in advance of requirements. An extra housing complete with all parts is provided with the machine, so that the stoppage for changing feeds is limited to the time required for releasing and removing one housing and substituting and securing the other.

Another feature of our invention lies in providing a quick throw-off for the roll feed, located within reach of the operator

feeding bars of stock to the machine, and affording instant relief, in case of the jamming of blanks in the dies.

Another feature of our invention lies in a straight line action machine in which the blank-feeding, pointing, transferring and the actuating mechanism for the header are all in the same straight line, avoiding the roundabout connections heretofore used for actuating the header. With this arrangement, we also preferably employ a forked member actuating the gripper, the fork straddling the direct header-actuating mechanism and being operated preferably from the same shaft. We also employ positive actuating mechanism for the gripper, both for raising it from contact with the spike blank, as well as for gripping the same, thereby obviating the jamming of the machine, which has heretofore resulted from other arrangements which lacked the positive raising of the gripper from contact with the spike blank.

Another feature of our invention lies in new and improved carrying mechanism for the nippers or transferring device, wherein we employ rotative bearings only and avoid the excessive wear and cutting, due to grit, scale and water, which accompanies the use of the reciprocating slides commonly used for carrying the nippers in machines of this character. Also, in independent adjustments for these nippers, whereby the longitudinal and lateral positions of their gripping members relative to the blank-holding die may either be changed, without change or interference with the other.

Other features of our invention relate to the device for simultaneously adjusting and maintaining the alinement of the rocker arm bearing blocks for the header ram, while positioning them to give the correct flow of the metal in forming the head of the spike. Also to arranging all the principal adjustments of the machine, so that they can be controlled from one side thereof.

The device comprises a continuously-rotated main driving shaft, which is connected by means of pawl-and-ratchet mechanism with the stock-feeding and blank-cutting rolls, which are intermittently rotated to cut and feed the blanks to a point where they are grasped by nippers, which carry the successive blanks forwardly and drop them into a two-part holding die, which is then closed to grip the sides of the blank, the top of the blank being engaged by a gripper so that the blank is approximately entirely inclosed within a holding die formed of the two die members and the gripper. The head is then formed by means of a heading tool, located between the two arms of the nippers and actuated by means of a direct connection with the main shaft.

The precise nature of our invention will

be best understood by reference to the accompanying drawings, which will now be described, it being premised, however, that various changes in the details of construction and general arrangements of the parts may be made, without departing from the spirit and scope of our invention, as defined in the appended claims.

In the drawings, the numeral 2 designates the main frame which comprises two vertical side members, the rear end member 3, a front member 4, and an intermediate member 5, connected together by means of transverse bolts 6. Resting on the front member 4, and held in position against the lugs 7, by means of the set screws 8, is a rectangular feed frame 9, which is provided with openings 10, for journal blocks 11, in which the spindles 12 of the stock feed rolls 13 are journaled. These blocks are held from lateral movement by means of cap plates 14, which are secured to the feed frame by bolts 15. This feed frame is also held in position with relation to the main frame and the end member 4, by means of bolts 16, which extend through lugs on the side members 2 of the main frame and set screws 8, which are threaded through lugs on one end and one side of the front member 4, and confine the base of the frame 9 against opposing lugs on the front member 4, thus providing a fixed position for the frame 9 in its relation to the front member 4, and to the main frame. Journaled in bearings in the main frame 2 is a shaft 17, which is constantly driven and is provided with a fly wheel 18. Journaled in bearings in the main frame is a shaft 20, and rotatably mounted on one end of this shaft is a bell crank lever 21, one arm 40 of this bell crank lever being connected to an eccentric rod 22, which is actuated by an eccentric 23, on the driving shaft 17. The other end of this bell crank lever is connected to one end of a link 22^a, the other end 45 of the link being connected to a pawl arm 24, which carries a spring-pressed pawl 25, for actuating the feed rolls. Pivotaly connected to the side of the front member 4 on the same side of the machine that the feed-operating mechanism is located is a bracket 26, which is rotatably mounted on a pin or bolt 26^a and is held in position by means of a bolt 27. 28 is an adjusting screw, for adjusting the position of the bracket for the purpose hereinafter described. Fixed in this bracket 26 is a short stud shaft 29, and mounted on this shaft 29 is a sleeve 30, on which is removably mounted a gear 31, and a ratchet wheel 32, which are connected to each other by means of a pin 33. The ratchet wheel 32 is connected to the sleeve 30 by means of the key 30^a, as can clearly be seen by reference to Fig. 17. The ratchet arm 24 is loosely journaled on the outer end 55 of the sleeve 30 and the sleeve and several

parts are held in proper position by means of a washer 34 and a nut 35, on the end of the shaft 29. The pawl 25 is formed integral with a short stud shaft 36, which has a bearing in the pawl arm 24, and connected to the outer end of this shaft 36 on the outer side of the pawl arm is a dog 37. Rotatably mounted on a bearing formed on the pawl arm 24 and concentric with the shaft 29 is a cam plate 38, which is held loosely to the side of the pawl arm 24 by means of a nut and washer on the shouldered stud 39; and 40 is a spring-pressed plunger seated in an opening in the pawl arm and made with a truncated cone on its outer end for engaging two suitable recesses, one formed in the base of the stem 40^a and the other in the inner face of the cam plate 38, so located as, in a measure, to lock the cam plate 38 in either of its two extreme positions, as shown in full and dotted lines in Fig. 16. Connected to this plate 38 is the operating stem 40^a, which extends in a lateral direction for shifting the cam plate to throw the pawl into and out of action. When the plate is in the full line position, the pawl 25 is held against the ratchet wheel 32 by means of the spring 41, and when the cam plate 38 is moved to the dotted line position, the cam plate 38 will engage and shift the dog 37 together with the pawl 25 to shift and hold the pawl out of engagement with the ratchet wheel and stop the feed of the stock. The operation of feeding the stock into the machine is accomplished by means of the feed rings 13^a, Fig. 29, which engage the lateral sides of the stock and carry it forward by friction.

The cutting rolls 13 do not engage the stock at their perimeter, but are provided with cutters 42, as can be seen by reference to Fig. 30, the number of which is equal to the number of ratchet teeth on the ratchet wheel 32. Connected to the outer ends of the roll spindles 12 are gear wheels 43, which are in mesh with each other, while the lower gear wheel is in mesh with the gear wheel 31, connected to the ratchet wheel 32, so that the blank-feeding rings and cutting rolls will be rotated one-fifth of a revolution for each revolution of the main driving shaft 17. The upper roll spindle bearing blocks 11 are adjusted by means of the adjusting screws 45.

In order to prevent the rolls from being rotated beyond the point to which they are advanced by means of the pawl 25, we provide a friction brake 46, which partially encircles the spindle of the upper roll and is connected to the frame 9 and is similar to the friction brake shown in Fig. 8.

In order to prevent the rolls from moving longitudinally, we form a neck 47 on the spindles thereof, each of which is engaged by a split collar 48 with a squared extension

48^a, which engages between lugs 49 on an extension 9^a of the feed frame 9. Connected to the split collars are eye-bolts 50, which, in turn, are connected by means of links 51 with eye-bolts 52, extending loosely through openings in the extension 9^a and connected to cross heads 53, there being two of such connections for each split collar.

54 designates set screws, there being one for each cross head 53, and they extend through threaded openings in these cross heads and engage plates 58, on the outer face of the extension 9^a.

56 designates bolts having spherical heads and also having screw-threaded connections with openings through the extensions 9^a; and journaled on these spherical heads are abutments 57, which engage the outer ends of the roll spindles, there being one screw and one abutment for each spindle. The abutments are arranged to prevent the spindles from moving in one direction, while the split collars and their link connections prevent the spindles from moving in the reverse direction. The link connections for these split collars are provided so as to enable the roll spindles to be adjusted for rolls of varying sizes.

If it is desired to change the machine to make spikes of a different length from the blank which is made by the machine as now set up, it will only be necessary to remove the ratchet wheel 32 and the gear 31, which is connected to it by the stud 33, and replace them with another ratchet wheel and another gear, each having the proper number of teeth, and to remove the feed frame, together with all parts attached thereto, and replace it with another feed frame and rolls having such a diameter and number of knives as will enable them to cut blanks of the length desired. If the rolls are of larger diameter than the rolls removed from the machine, it will readily be understood that gears of larger diameter than gears 43 will be used in place thereof which will be increased in proportion and in that case, another gear 31 of larger diameter, together with the ratchet wheel, must be replaced, so that the three gears will be one to one. In this case, the bracket 26 will be swung around the pin 26^a, and after the gears are adjusted in proper mesh by means of the screw 28, the bracket will be secured in position by means of the bolt 27.

In order to avoid breaking the roll-driving mechanism, if the stock should become jammed between the rolls, we provide the eccentric rod 22 with a slot 59, in which is mounted a journal block 60, for the pin on the bell crank lever 21. This block is held in position in the slot by means of the set screw, which presses it against a breakable pin 59^a, which extends through the walls of the slot. The length of this slot is slightly

greater than the length of the throw of the eccentric, plus the length of the block and the diameter of the breakable pin 59^a. The arrangement is such that if the rolls should become jammed, the pin 59^a will be sheared off by means of the block 60, before sufficient power to break the driving mechanism has been exerted, thereby avoiding breakage of any of the important parts.

The numeral 61 designates a turn-buckle having right and left hand threads, which are connected to the threaded portions of two members forming the link 22^a, and is arranged for adjusting the link to bring the pawl 55 to the proper point at the end of the feeding stroke.

Blank-holding die and operating mechanism.—The cut and pointed blanks are carried forward from the cutting rolls by nippers, as hereinafter described, to a holding die in which the body of the blank is fixedly held, while the blunt end thereof is upset and headed by means of a heading tool. The holding die is secured upon a supporting block 62, which is secured to the main frame 2, immediately adjacent to the feed roll frame. Mounted in this supporting block is a stationary die block 63, which is provided at one side thereof with an anvil member 64, having a ledge 65 and a side portion 66, which form two of the walls of the holding die. Slidably mounted in a guide in the supporting block 62 is a movable die block 67, the side adjacent to the stationary die block being provided with an anvil member 67^a, the upper portion thereof forming another wall for engaging the blank. 68 is an ejector which is slidably mounted in a groove in the supporting block 62, below the die blocks and is connected to the movable die block by means of a pin 69. This ejector extends under the stationary die block 63, which is recessed to receive a head portion 68^a, loosely carrying two pins 68^b, which extend in a horizontal direction through openings in the side portion 66 of the anvil member 64 of the stationary die block. The ejector is arranged to be moved laterally by means of the pin 69, when the dies are opened, and the pins 68^b engage the finished spike and move it from the ledge 65, so that it will drop into an inclined chute 70, in the supporting block and fall into any suitable conveying device for carrying off the finished spikes.

One side of the movable die block 67 is provided with a rib 71 and a groove 72, parallel with each other, but at an acute angle with relation to the longitudinal center of the machine. Slidably mounted on the guiding surface of the supporting block 62 and a surface on one of the side members of the frame 2 is a wedge block 73, having a downwardly extending rib 74, and a groove 75; the rib 74 being seated in the groove 72

of the movable die block 67, while the rib 71 on the die block 67 is seated in the groove 75 of the wedge member, the arrangement being such that when the wedge block is moved forwardly, the movable die block will be moved toward the stationary die block to inclose the blank within the die.

The wedge block 73 is moved by means of the main shaft 17, through the medium of a double cam 76, connected thereto. This cam is provided with cam faces 77 and 78, which engage rollers 80 and 79, respectively, on a rock arm 81, which is pivotally connected at 82 to the frame of the machine. Connected to this rock arm 81 is a link 83, the other end of which is connected to a crank 84, which is, in turn, connected to a shaft 85, journaled in bearings in the frame of the machine.

20 The numeral 86 designates toggle levers which are connected to the shaft and the wedge block 73, so that when the shaft 85 is rotated in one direction, the wedge block will be moved to open the die. By providing a cam having two faces for moving the wedge block, we are enabled to quickly close and open the die, and provide considerable dwell between the opening and closing movements. In order to provide a breakable connection in the die-operating mechanism, the end of the link 83 is slotted at 87 and mounted therein is a block 88, in which the pin on the crank 84 is journaled. The block is held in position in the slot by means of a set screw and a breakable pin 87^a, which will be sheared by the block 88 when a predetermined pressure has been reached, in order to avoid breaking any of the die-operating mechanism, in a manner similar to the action of the breakable connection in the stock-feeding mechanism. This link 83 is also provided with a turn-buckle 89, for adjusting the length thereof.

45 *Gripper mechanism.*—The die just described engages the two sides and bottom of the blank, while the top of the blank is engaged by means of a gripper, so that the four sides of the blank are positively engaged to form an inclosing die for the blank when it is being headed, and thereby prevent distortion of the sides thereof.

The numeral 90 designates the gripper proper, which is seated in a recess in one end of a walking beam 91 and is held therein by means of hook bolts 92. This walking beam is connected to a shaft 93, journaled in links 94, which are slidably mounted in vertical guides in the frame of the machine. The lower ends of these guides are connected to each other by means of a tie rod 95, which passes through weighted levers 96, pivoted to brackets 97, secured to the inner sides of the frame of the machine, there being one of these levers at each side of the machine.

65 The upper ends of the links 94 are pro-

vided with shoulders 98, which are adapted to engage the tops of the guides for these links and form stops which support the gripper mechanism, when the gripper 90 is in the raised position. The end of the walking beam 91 opposite the end holding the gripper proper is forked, and connected to each of these forked members is an adjustable bracket 99, each bracket having a roller 100, which rollers are engaged by cams 101 on the main driving shaft 17. These cams are arranged to raise this end of the lever and move the gripper downwardly on the top of the blank, and the pressure of the gripper on the blank is determined by the position of the weight 102 on the levers 96, as previously described. The walking beam is rocked about the axis of the shaft 93, by means of the cams 101 until the predetermined amount of pressure has been applied to the top of the blank, and as soon as this point has been passed, the weight 102 will be raised by means of the links 94 and levers 96. By adjusting the weights 102 along the levers 96, or by placing larger or smaller weights on these levers, the pressure of the gripper on the blank can be varied.

50 *Nipper mechanism.*—The nipper mechanism comprises arms 103, each of which is pivoted to a pin 104, extending upwardly from a carriage 105. The end of each of these arms is provided with a removable jaw member 106, which is arranged to grip the cut and pointed spike blank and transfer it from the rolls to the die. Each of the arms 103 comprises an upper and a lower member, the upper member having the jaw 106, while each of the lower members is provided with an upwardly extending pin 107, which registers with openings in their respective arms. The rear ends of the lower members of the arms are connected to links 108, which are, in turn, connected to bell cranks 109, the other ends of these bell cranks being connected by links 110 to arms 111, keyed to a shaft 112, journaled in bearings on the frame of the machine. The bell cranks 109 are pivotally connected to a slide 113, adjustably mounted in a guide in the carriage 105, so that the nippers can be centrally positioned with relation to the die and rolls. The carriage 105 is pivotally connected to a plurality of short cranks 114 at the rear end, which are keyed to the shaft 20, previously described, while the front end of this carriage is pivotally connected to a yoke 114^a, secured to a shaft 114^b, journaled in bearings through the main frame of the machine. The links 110 are provided with turn-buckles 115, for adjusting the lengths thereof, in order to adjust the arms 103 relatively to each other for the proper gripping of the blank. Connected to one end of the shaft 17 is a disk 116, having a crank pin 117, to which is connected one end of a link 118.

118, the other end of this link being connected to a slide block 119, adjustably mounted in an arm 120, secured to the shaft 112. Extending upwardly through the arm 120 and the shaft 112 into the slide block 119 is an adjusting screw 121, having a hand-wheel 122, for raising and lowering the slide block to adjust the stroke of the arm 120 and the movement of the shaft 112, which actuates the nippers and carriage, as hereinafter described.

Connected to the main frame of the machine at the one side thereof is a brake device comprising a pair of adjustable jaws 123, which partially encircle and frictionally engage a disk 124, keyed to the shaft 20, and which is arranged to frictionally hold the carriage against free movement.

The brake device which is connected to the shaft 20 is arranged to frictionally hold the carriage 105 against movement in either direction until after the nippers have been moved to full open position, or into engagement with the blank piece to be transferred to the dies.

The nippers have been shown in their full open positions in Fig. 14 and in their closed positions in Fig. 15. Assuming the parts to be in the position shown in Fig. 15, in which the nippers have been closed on the blank by movement of the rods 110 to the right, the blank will be moved from the cutting rolls over the die, the nippers being moved to the dotted line position shown in Fig. 15. The movement of the rods 110 is now reversed, and as they are moved to the left, the frictional brake will hold the carriage 105 from movement while the nippers are being opened to the position shown in full lines in Fig. 14. This opening of the nippers is caused by the frictional brake restraining the carriage 105 from movement, as the work required to move the carriage is greater than the work required to open the nippers. As soon as the nippers have been opened to the position shown in full lines in Fig. 14 so that the projections 141 engage each other and thereby prevent any further movement of the nippers, the further movement of the links 110 will advance the carriage by overcoming the friction of the brake to bring the nippers to the dotted line position shown in Fig. 14. The links 110 are then moved to the right, and the first movement will close the nippers on the blank to be transferred and, as soon as the pressure against the blank is great enough to overcome the frictional resistance of the brake, the carriage, together with the nippers, will be moved to the right to transfer the blank to a point over the die.

Header.—After the blank has been fed to the die and has been gripped therein, the blunt end thereof which protrudes beyond the dies is upset and headed against the end of the

inclosing die and the gripper, so that the bottom of the head will be die-formed around the entire spike to form a perfect head, which will be properly shaped, to engage the flange of a railroad rail at the front end, while the rear end will be properly shaped to be engaged by the usual withdrawing claw bar.

The heading tool 125 is removably connected to a ram 126, pivotally connected to a yoke 127, secured to a shaft 128 in bearings 129, adjustably mounted on the frame of the machine, as hereinafter described. The rear end of this ram is pivotally connected to a lever 130, on a shaft 131, journaled in bearings on the main frame. 132 is an eccentric rod connected to the lever 130 and encircles an eccentric 133, on the main driving shaft 17, so that the ram, together with the heading tool, makes a complete reciprocation for each revolution of the main driving shaft. This ram is located above the npper carriage and between the arms of the nippers and in direct line with the blank die and feeding rolls. The bearing blocks 129

for the shaft 128 are slidably mounted on arc-shaped surfaces on brackets 134, secured to the main frame of the machine, and are provided with undercut grooves or guides, for receiving hook-shaped bolts 135, for securing the bearing members 129 in their adjusted positions on the brackets 134. Extending downwardly from each of these bearing blocks 129 and into the grooves 134 are hook-sectioned ribs 136, which are provided with rack teeth which engage pinions 137, firmly secured to a shaft 138, the outer end of which is provided with a crank 139. This crank 139 is for rotating the shaft and simultaneously positioning both of the bearing blocks 129 in order to adjust the height of and the position of the arc described by the front end of the heading tool 125. On the end of shaft 138, outside of crank 139, is threaded the star wheel 110 nut 140. After the bearing blocks 129 have been properly positioned by rotation of the shaft 138, they are secured against further movement by tightening the nut 140 and thereby clamping the adjacent gear 137 into immovable engagement with the bearing blocks 129. The hook bolts 135 are provided for additional security when needed.

Operation.—The operation is as follows; assuming the parts to be in the position shown in Fig. 2 of the drawings, in which the parts are in the positions indicated on the diagram illustrated in Fig. 34 at the point marked "zero." This diagram has been laid off in points of 30 degrees from zero to 360 degrees.

In Fig. 2, the blank has been gripped by the nippers and almost moved to its position over the die, while the movable member of the die has been moved to almost its

closed position, the gripper mechanism being about ready to descend and the header at the turning point to advance to head the blank. During the further movement of the shaft 17, the links 110 will be drawn to their full rearward positions to bring the blank over the die and immediately advanced; and as the carriage 105 for the nippers is held by the frictional brake 123, the forward movements of these links will first open the nippers to release the blank and permit it to drop into the dies just before closing of same, which takes place at a point slightly beyond the 30 degrees mark on the diagram. These links 110 will be advanced until the abutments 141 on the bell-cranks 109 of the nipper mechanism engage each other, when the further opening movement will be stopped and the further forward movement of the links 110 will advance the carriage 105 to carry the nippers forward into position to grasp the next blank, which position is reached shortly after the 210 degrees mark on the diagram. Immediately after the blank has been dropped into the die, the gripper will close down on the blank, which has been inclosed in the die, and will engage it between the 60 degrees and 90 degrees points on the diagram. At this time, the header is advancing and will upset the head close to the 180 degrees point and immediately afterward recede. The feeding mechanism is so arranged that the end of the feed for the next blank will be completed just before the 90 degrees point on the diagram, and as the cutters do not completely sever the blank, it will be held until the nippers close upon it for the next cycle of operations. Shortly after the header has completed its forward stroke and is receding, the gripping tool is raised and the movable die is moved to open the die and remove the finished spike from the ledge on the stationary die, by means of the pins on the ejector, to discharge it into the chute 70, which action takes place shortly after the 180 degrees point. Shortly after the 210 degrees point, the links 110 will be moved rearwardly, and as the nipper carriage 105 is held by means of the friction brake, the nippers will close in on the blank, and as soon as the grip of the nippers upon the blank is sufficient to overcome the resistance of the frictional brake, the carriage, together with the nippers and the blank, will be moved rearwardly to carry the blank over the open die. As soon as the links 110 reach their rearmost position, they will be advanced to open the nippers and permit the blank to drop into the die, which is being closed, for grasping the blank for the next heading operation.

The advantages of our invention result from the provision of means for feeding,

cutting and pointing spike blanks and conveying them to a die or holding device which is arranged to be opened, to permit the ready removal of the finished spike, and in which there is a complete backing formed for the head of a spike struck up by a heading tool. Also, from the provision of means for conveying the blank forward in a line with a feeding and pointing mechanism by means of nippers which straddle the header mechanism. Further, from the provision of an oscillating carriage for the nippers, which has a forward and a rearward movement, which materially assists in separating the pointed blank from the next blank at the point thereof. Another advantage resulting from this type of carriage lies in the fact that rotary bearings are provided for the nipper carriage, so that there is no danger of cutting out the bearings by means of the scale from the spikes, such as occurs in spike machines when using a reciprocating carriage having cross heads which work in guideways.

Still another advantage results from the provision of means for simultaneously adjusting the bearings on both sides of the machine for the shaft carrying the front end of the header ram, so that said header ram can be adjusted from one side of the machine, and at the same time, insure an equal adjustment of the shaft bearing members to retain the parts in proper alignment.

A further advantage results from the provision of feed rolls, together with the driving gears, mounted in an auxiliary frame, which is removably connected to the main frame, so that the entire blank-feeding and cutting mechanism can be removed and replaced by another blank-feeding device, in order to make repairs or change the machine for making spikes of different sizes. By this arrangement, a great deal of time is saved as the repairs and changes can be made in the machine shop, so that the spike machine can be in operation at all times.

An advantage is also gained through the relative positions of the gripper and header mechanisms, which perform the most strenuous work of the machine. By being made central with each other and on the center line of the machine, they are both actuated by that portion of the main driving shaft which extends between the bearings of said shaft in the main frame. Thus the working stresses are properly provided for and simple direct action is obtained for both mechanisms.

We claim:

1. In an automatic spike machine, a die made in a plurality of parts and arranged to inclose a spike blank on the bottom and two sides only, connections for relatively moving said parts toward and from each other, cutting and pointing mechanism, and a me-

chanical transfer device arranged to grip and transfer the blank from the cutting and pointing mechanism into the cavity of the die through the open end thereof, substantially as described.

2. In an automatic spike machine, a receiving die made in a plurality of parts and arranged to inclose a spike blank on the bottom and two sides only, mechanism for relatively moving said parts toward and from each other, mechanism for cutting and pointing a blank, transfer mechanism arranged to carry the cut blank to a position above the die, and a gripper arranged to engage the top face of the blank in the die for heading, substantially as described.

3. In an automatic spike machine, an open top side-opening die having a plurality of parts, mechanism for moving the die parts laterally relatively to each other to grip the blank, a vertically moving gripper arranged to engage the top of the blank and coacting with the die to hold the blank and completely inclose the four sides thereof, mechanism for cutting and pointing a blank, and a transfer mechanism arranged to carry the cut blank to a position above the cavity of the die and below the gripper; substantially as described.

4. An automatic spike machine, comprising a main frame, an auxiliary frame removably mounted thereon, feeding rolls journaled in said frame, blank-cutting and pointing knives in said rolls, driving gears on said rolls, and roll-actuating mechanism mounted on the main frame including a gear meshing with one of the gears on the rolls, substantially as described.

5. An automatic spike machine, comprising a main frame, an auxiliary frame removably mounted thereon, feed rolls journaled in the auxiliary frame, blank cutting and pointing knives on said rolls, a driving shaft rotatably mounted on the main frame, a gear wheel mounted on the auxiliary frame and meshing with a gear wheel on the shaft of one of the rolls, and intermittently operated actuating connections between the driving shaft and the adjustably mounted gear wheel substantially as described.

6. An automatic spike machine, comprising blank feeding, cutting and pointing mechanism, a holding die, a carriage, oscillating lever mechanism for supporting the carriage, nippers mounted on said carriage, a friction device coacting with the carriage supporting mechanism and arranged to cause the nippers to be opened or closed before the carriage is moved, and an operating device arranged to actuate the nippers and move the carriage to transfer the blank from the cutting and pointing mechanism to the die, substantially as described.

7. An automatic spike machine, comprising blank feeding, cutting and pointing

mechanism, a holding die, a carriage, oscillating lever mechanism for supporting the carriage, nippers mounted on said carriage, a friction device coacting with the carriage and arranged to cause the nippers to be opened or closed before the carriage is moved, operating mechanism arranged to actuate the nippers and move the carriage to transfer the blank from the cutting and pointing mechanism to the die, means for closing said die upon the blank, and a gripper arranged to hold said blank in the die, substantially as described.

8. An automatic spike machine, comprising blank feeding, cutting and pointing mechanism, a holding die, a carriage, oscillating lever mechanism for supporting the carriage, nippers mounted on said carriage, a friction device coacting with the carriage and arranged to cause the nippers to be opened or closed before the carriage is moved, operating mechanism arranged to actuate the nippers and move the carriage to transfer the blank from the cutting and pointing mechanism to the die, means for closing said die upon the blank, a gripper arranged to hold said blank in the die, and a header for upsetting the end of the blank to form the spike head, substantially as described.

9. An automatic spike machine, comprising blank-feeding, cutting and pointing mechanism, a holding die, an oscillating carriage, nippers mounted on said carriage, and means for independently adjusting the lateral and longitudinal positions of said nippers relative to said holding die, substantially as described.

10. An automatic spike machine, comprising blank-feeding rolls, cutters on said rolls for cutting and pointing spike blanks, a die in the line of feed of said blanks arranged to inclose three sides of the blank, said die having a stationary member and a movable member, means for moving the movable die member laterally relatively to the stationary member, oscillating nippers arranged to transfer the blanks directly from the feeding and cutting-off rolls to the die, and actuating mechanism for the nippers, substantially as described.

11. An automatic spike machine, comprising blank cutting and pointing mechanism, a two-part die member arranged to inclose a spike blank on the bottom and two sides, means for moving one of said die members laterally relative to the other, said parts engaging the two sides and bottom of the blank, a gripper for engaging the top of the blank, and arranged to enter the space between the two parts of the die member, substantially as described.

12. An automatic spike machine, comprising blank cutting and pointing mechanism, a blank holding die, said die being arranged

to engage three sides of the blank, means for opening and closing said die, a gripper for engaging the fourth side of the blank and arranged to enter the cavity of the die, and positive means for moving said gripper to and from engagement with the blank, substantially as described.

13. An automatic spike machine, comprising intermittently operated blank-cutting and pointing mechanism, a two-part die member, means for moving the parts of said die member laterally relative to each other, said die member engaging the two sides and the bottom of the blank, a gripper for engaging the top of the blank and arranged to enter the space between the two parts of the die member, means for raising and lowering said gripper, and a compensating device connected to said gripper arranged to apply a predetermined amount of pressure to the blank, substantially as described.

14. An automatic spike machine, comprising blank-feeding and pointing mechanism, means for operating said mechanism, a die having a plurality of parts movable laterally relative to each other, said die being arranged to engage three sides of the blank, means for moving the die members relatively to each other, oscillating nippers for transferring the blank directly from the feeding mechanism to the die, actuating connections for operating the nippers, a header located between the nippers, and actuating mechanism for operating the header, substantially as described.

15. An automatic spike machine, comprising intermittently operated blank-feeding and pointing mechanism, a die having two parts movable laterally relatively to each other, means for moving said parts relatively to each other, a gripper for holding the blank in the die, said die parts and gripper being arranged to form the entire underside of the spike head, nippers for transferring the blank from the feeding mechanism directly to the die in a line with the feed of the stock, an oscillating header, and means for oscillating said header, substantially as described.

16. Nipper mechanism for transferring a blank to the dies of a spike machine, comprising a carriage, a plurality of shafts on which the carriage is movable, lever mechanism connected to said shafts and the carriage, a friction device connected to one of said shafts, lever arms pivotally connected

to the carriage, bell cranks connected to said carriage, links connected to said bell cranks and the nipper arms, and operating mechanism connected to the crank arms arranged to open and close the nippers and move them bodily with the carriage to transfer the blank, substantially as described.

17. An automatic spike machine, comprising a main frame, blank-feeding and pointing rolls, actuating mechanism for said rolls connected thereto and to the main driving shaft, a two-part die arranged to engage three sides of the spike blanks, actuating mechanism connected to one member of said die and the main driving shaft for opening and closing the die, a gripper for holding the blank in the die, means on the main shaft for actuating said gripper, nippers for transferring the blanks in a longitudinal direction from the feeding and cutting mechanism, directly to the die, actuating connections for said nippers connected to the main driving shaft, a header for upsetting the end of the spike blank and forming the head, an eccentric on the main driving shaft, and actuating connections between the eccentric and the header, substantially as described.

18. An automatic spike machine, comprising a two-part die, means for moving one of said parts relatively to the other, means for transferring a blank to said die, means for forming a head on said blank, and an ejector connected to the movable part of the die and extending through the stationary part thereof arranged to eject the finished spike from the die when the movable member is moved away from the stationary member, substantially as described.

19. An automatic spike machine having a header, a plurality of shafts for supporting said header, a plurality of bearings for one of said shafts, and means for simultaneously adjusting both of said bearings to adjust the header, substantially as described.

In testimony whereof, we have hereunto set our hands.
